(57) **CLAIM**

The ornamental design for a shower head, as shown and described.

DESCRIPTION

In a preferred embodiment, the nature of this product is as a shower head primarily useful for enabling a water spray from a plumbing fitting.

FIG. 1 is a right, top, front perspective view of a shower head embodying my new design;

FIG. 2 is a front elevational view thereof;

FIG. 3 is a right side elevational view thereof, the left side elevational view being a mirror image of the right side shown;

FIG. 4 is a top plan view thereof; and,

FIG. 5 is a rear elevational view thereof.

The broken line representations of a face plate and nozzles in FIGS. 1 and 2, of a tab in FIGS. 1-4, and of mounting structure in FIG. 5, are for the purpose of illustration only, and form no part of the claimed design.
